UNITED STATES PATENT OFFICE

DANIEL C. MULVIHILL, OF HANNIBAL, MISSOURI

RAILWAY CROSSING

Application filed November 21, 1928. Serial No. 320,893.

This invention relates to railway crossings.

The principal object of the invention is the provision of new and improved units for forming a railway crossing, together with new and improved means for securing the units in position to form the crossing.

Another object of the invention is the provision of a new and improved railway crossing that is provided with new and improved means for maintaining the two running rails insulated from each other.

A further object of the invention is the provision of a new and improved railway crossing that is cheap to manufacture, easily installed, efficient in use, that may be readily removed for repairs, and that is composed of a minimum number of parts.

Other and further objects of the invention, and advantages thereof, will appear from the following description taken in connection with the accompanying drawings, in which

Fig. 1 is a perspective view of a railway crossing, with parts in section;

Fig. 2 is a perspective view of one of the end plates or units;

Fig. 3 is a perspective view of one of the anchoring devices;

Fig. 4 is a vertical section of a railway track and auxiliary rails, showing crossing units in position therein;

Fig. 5 is a longitudinal section of the crossing;

Fig. 6 is a transverse section of a modified form of crossing;

Fig. 7 is a longitudinal section of a portion of a railway showing a modified form of construction in position thereon; and

Fig. 8 is a plan view of one of the anchoring members.

Referring now to the drawings, the reference characters 10, 10, designate the running rails which are supported by ties 12 or the like in the usual manner.

It is desirable that the crossing be made in separate units so that it may be readily applied in position or removed for replacement or repairs. In order to avoid the use of bolts and nuts or other fastening means for connecting the units, these units may be cast with integral supports and provision made for in-

terlocking the supports to the running rails.

In the form of construction selected to illustrate one embodiment of the invention, a supplemental plate supporting element is employed between the running rails. This element is provided with a channel at each side thereof for receiving the ends of the supports for the plate units as will presently appear.

In the form of construction shown in Fig. 1, this element is in the form of a single railway rail 13. This rail extends the full width of the crossing. A plurality of crossing or plate units 14 are employed between each running rail and the supplemental rail 13.

Each plate unit comprises a plate member 15 and a supporting member 16 under each end portion thereof. For convenience of description the plate members 14 will be considered as extending longitudinally of and parallel with the running rails, although in actual practice their greater dimension extends transversely of the tracks.

The supporting members 16 are preferably set in from the ends of the plate to provide clearance. These members extend beyond the side edges of the plate and are adapted to engage the flanges 17 and 18 beneath the balls 19 and 21 of the running and auxiliary rails 10 and 13, respectively. One side of each plate member 15 is provided with a depression 22 for providing clearance for the flanges of railway trains. Only one depression need be provided in each plate member because the plate units are duplicates and may be used interchangeably at either side of the track, thus eliminating the necessity for providing rights and lefts.

The plate and supporting members are preferably cast integral, thereby obviating the use of bolts, screws or other means for attaching the supporting members to the plates.

The parts are so constructed that the width of the plates 15 fills the space between the balls of the adjacent rails, and the projecting ends 23 and 24 of the supporting members 16 rest on the flanges 17 and 18 directly beneath the balls of the adjacent rails. By means of this arrangement, the plate units will be supported by the rail flanges and prevented from

vertical movement by the balls of said rails.

In assembling the crossing after the supplemental rail has been placed in position, the crossing or plate units 14 are slid in from either or both ends of the supplemental rail 13 as will be readily understood from an inspection of the drawing. The units being duplicates of each other, the plate members will be in alinement to provide a smooth crossing. The units are preferably in end to end contact with each other when the crossing is assembled and are held from moving along the rails by any suitable means.

In the form of construction shown, an end member 25 is employed for this purpose at each end of the crossing. This member has a flange or horizontal portion which is adapted to be attached to the outer end 26 of the outermost plate 140 as by bolts 27 or the like. It extends downwardly and forwardly and is provided with a lower flange 28 which is adapted to be secured to the ties as by means of the bolts 29.

The approaches at each end of the crossing may be made by employing an auxiliary or supplemental rail 31 spaced outwardly from the running rails at each side of the track. Each of the rails 31 may be placed at the inner margin of the concrete or other road bed 30 material of the highway 32. A plurality of plate units 33 similar to the plate units 14, except that they are not provided with grooves or depressions, are employed. Each unit comprises the plate 34 and supports 35 cast integral therewith and extending beyond the side edges thereof for engaging the flanges 36 and 17 beneath the balls 37 and 19 of the supplemental and running rails, as in the previous construction.

In Fig. 6 of the drawing is shown a modified form of construction adapting applicant's invention to railways employing signal system. This form of construction differs from that previously described in that the supplemental plate supporting element 40 comprises a pair of intermediate or supplemental rails 38 and 39 spaced a short distance apart and interposed between the running rails 10, 10. These rails are separated a sufficient distance to insure that their flanges 41 and 42 are not in contact with each other.

A plurality of block units 43, preferably of the same length as the plate units, are inserted between the rails 38 and 39. Each block unit 43 has its upper portion reduced as at 45 to pass between the balls of the rails 38 and 39, the base portion of the block being adapted to rest on the flanges 41 and 42 beneath the balls of said rails.

The block units 43 may be made from any suitable insulated material, as wood or the like. Plate units 44 having supporting members 46 extending laterally beyond the side edges of the plates for engaging in the channels in the supplemental plate supporting

element 40 and the running rails, are employed to form the crossing, the same as in the previous construction. Each plate is provided with the depression 47 along one side edge for providing clearance for the car wheel flanges and is also provided with a plurality of the supports 46, the projecting ends of which engage in the channels of the running and supplemental rails in the manner disclosed above.

The block units 43 and the plate units 44 are inserted and removed in the same manner as the plate units 14 described above. The end block units are adapted to be anchored in any suitable manner to the ties or road bed.

The construction shown in Fig. 6 is intended to be used to insulate the running rails from each other where a signal system is employed. Instead of employing the arrangement shown in Fig. 6, satisfactory results may be obtained by employing insulating material between the plates 14 and the running rails for insulating said rails from said plates.

In Figs. 7 and 8 is shown a modified form of end plate units and anchoring device.

In this form of construction the end plate units 51 which correspond to the end plate units 140, see Fig. 1, are provided with downwardly and outwardly extending flanges 52 to which may be connected as by means of rivets or the like attaching strips 53 which have their outer ends rigidly attached to the ties as by means of spikes or the like 54.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. In a railway crossing, a pair of running rails, a supplemental rail between said running rails, a plurality of plate units between certain of said rails, each unit comprising a plate having a depression at one side edge thereof for providing clearance for the flange of a car wheel, and a plurality of supports extending laterally beyond the side edges of said plate for engaging the flanges of said rails beneath the balls thereof for supporting said plates in the plane of said balls and for preventing the removal of said plates vertically.

2. In a railway crossing, a pair of running rails, supplemental plate retaining means between said rails, said means comprising a pair of conventional railway rails spaced apart, a block of insulating material between said rails and slidably on the same, said block having lateral extensions for engaging between the balls and flanges of said rails, a plurality of plate units between each of said

running rails and said retaining means, a plurality of plate units, a plurality of supports integral with each unit and extending beyond the side edges thereof for engaging in the channels of said running rails and said means, for forming a crossing, and means for anchoring the end units of said crossing.

3. In a railway crossing, a pair of track rails, the ball and flanges of each rail forming a channel at each side thereof, a plate retaining element between said rails, said element comprising a pair of conventional railway rails spaced apart, a block of insulating material between said rails and slidable on the same, said block having lateral extensions for engaging between the balls and flanges of said rails, a plurality of plate units adapted to engage the channels of said track rails and said plate retaining element at each side thereof, and means for anchoring the end plates from movement longitudinally of said tracks.

In testimony whereof I affix my signature
DANIEL C. MULVIHILL.
